(57) **CLAIM**

An ornamental design for an earring, as shown and described.

DESCRIPTION

FIG. 1 is a front perspective view of an earring;
 FIG. 2 is a front side view of the earring;
 FIG. 3 is a back side view of the earring;
 FIG. 4 is a right side view of the earring;
 FIG. 5 is a left side view of the earring;
 FIG. 6 is a bottom side view of the earring; and,
 FIG. 7 is a top side view of the earring.
 Broken lines shown in drawings illustrate portions of the earring that form no part of claimed design.
